(57) **CLAIM**

The ornamental design for a unisex urinal as shown and described.

DESCRIPTION

1. Unisex urinal
- 1.1 : Perspective
- 1.2 : Perspective
- 1.3 : Left
- 1.4 : Right
- 1.5 : Front
- 1.6 : Top

The characteristic features of the designs lie in the shape of the portions shown in solid lines; In profile, the outer edge of the urinal characterizes itself as follows: the line (edge) goes down at an angle, makes a curve and finally ends up more or less horizontal; In top view, the area in which urination takes place is wider and slowly narrows toward away from the large flat area (the back of the urinal).
